UNITED STATES PATENT OFFICE.

EVERETT McDILL, OF SPARTA, ILLINOIS.

MAIL-RECEPTACLE SUPPORT.

1,377,084.

Specification of Letters Patent.

Patented May 3, 1921.

Application filed July 8, 1920. Serial No. 394,665.

To all whom it may concern:

Be it known that I, EVERETT McDILL, a citizen of the United States, and resident of Sparta, in the county of Randolph and 5 State of Illinois, have invented a new and Improved Mail-Receptacle Support, of which the following is a full, clear, and exact description.

This invention relates to supports for 10 mail boxes or receptacles and is particularly designed for use in rural districts.

The primary object of the present invention is to provide means for revolvably supporting a plurality of mail containers or receptacles from a single supporting standard whereby the standard may be positioned within a fence at one side of the road in such a manner as to allow the different receptacles to be successively exposed beyond the 20 same for the insertion or removal of the mail therefrom.

Another object of the invention is to provide a device of the character described which is so constructed as to prevent rusting or freezing of the movable elements 25 which would hinder its operation.

A further object of the invention is to provide a device of the character described which is simple in construction, inexpensive 30 to manufacture and which may be readily installed at a minimum expense.

With these and other objects in view, some of which will be more apparent hereafter, reference is made to the following description, 35 claims and accompanying drawings, in which—

Figure 1 is a fragmentary side elevation with parts in section to disclose the underlying structure.

40 Fig. 2 is a fragmentary plan view thereof. Fig. 3 is a detail cross sectional view taken on the line 3—3 of Fig. 1.

Fig. 4 is a similar view taken on the line 4—4 of Fig. 1.

45 Referring to the drawings, which illustrate the preferred embodiment of the invention, 10 designates a post or standard here illustrated as of hollow cylindrical formation which is provided adjacent its upper 50 open end with an annular groove 11. A hub 12 having a vertical bore 13 closed at its upper end is provided and is adapted to be rotatably mounted on the upper extremity of the standard 10. A collar 14 is adjustably arranged on the standard and retained 55 in its adjusted positions by means of a set

screw 15, said collar constituting a bearing for the lower end of the hub. A set screw 16 is threaded through the upper end of the hub and is designed to co-act with the annular groove 11 to provide an auxiliary means for supporting the hub and also as a means for locking the same against rotation on the standard. The hub 10 is further provided with an annular boss 17 having radial 60 threaded openings 18 which are adapted to receive the inner threaded extremities 19 of the radial supporting arms 20. The supporting arms 20 are preferably square in cross section and are provided with a plurality of transverse openings 21. Transverse horizontal supporting clamps 22 are longitudinally adjustable on the supporting arms 20 and the same comprise a lower member 23 having a rectangular depression 75 24 for the reception of the supporting arm, and an upper member 25. The rectangular depression 24 is provided with aligned apertures for the reception of a retaining bolt 26 which is adapted to pass through any one of 80 the transverse openings 21 in the supporting arm. The bottom wall of the mail container is adapted to be clamped between the upper and lower members 25 and 23 by means of 85 the bolts 27. As illustrated a parcel post basket 28 and a mail box 29 are respectively supported from each arm.

In use of the device the standard is preferably positioned with a fence at the side of the road in such a manner as to permit the 90 arms to be successively exposed beyond the fence to permit of the insertion or removal of mail from the containers or receptacles 28 and 29. The hub 12 constitutes a housing for the upper open end of the standard and 95 shields the same from moisture to prevent the formation of rust or ice which would tend to obstruct the operation of the device.

While there has been illustrated and described a single and preferred embodiment 100 of the invention, no limitation is necessarily made to the precise details of construction therein exhibited and it is understood that variations and changes which fall within the scope of the appended claims may be 105 resorted to when found expedient.

Having thus described my invention, I claim as new and desire to secure by Letters Patent:—

1. A mail receptacle support comprising 110 a vertical tubular standard, a tubular hub having a closed upper end adapted to be

telescopically received by the upper end of said standard for rotatably associating the hub therewith and for closing the upper end of the standard, a plurality of supporting arms extending radially from the hub, means for supporting and securing a plurality of mail receptacles thereon for effecting permanent longitudinal adjustments of the same, and means carried by the hub and adapted 10 to co-act with the standard for locking the same against rotation.

2. The combination with a mail receptacle support including a vertical standard, a rotary hub and a plurality of supporting

arms extending radially therefrom, of means 15 for associating a plurality of receptacles with the supporting arms to permit of longitudinal adjustments of the same thereon comprising a pair of strips between which the bottom of the receptacle is adapted to be arranged, means for clamping said strips to the bottom of the receptacle, the lower strip having a medial offset portion adapted to receive and embrace the supporting arm, and means for securing said lower strip to 25 the supporting arm.

EVERETT McDILL.
